UNITED STATES PATENT OFFICE.

EDWARD L. SANDS, OF WEBB CITY, MISSOURI.

PEN AND PENCIL HOLDER.

No. 884,865.

Specification of Letters Patent.

Patented April 14, 1908.

Application filed June 27, 1907. Serial No. 381,173.

To all whom it may concern:

Be it known that I, EDWARD L. SANDS, a citizen of the United States, residing at Webb City, in the county of Jasper and State of Missouri, have invented certain new and useful Improvements in Pen and Pencil Holders; and I do declare the following to be a full, clear, and exact description of the invention, such as will enable others skilled in the art 10 to which it appertains to make and use the same.

This invention has relation to new and useful improvements in pen and pencil holders, and has for its object the production of a simple, economical and novel device of this character whereby a pen or pencil may be readily attached to a vest or other garment so as to keep the same at hand and ready for use at all times, and liability of the pen or pencil becoming misplaced or lost, and the annoyance or inconvenience caused thereby is eliminated.

With the foregoing and other objects in view, the invention consists of certain novel features of construction, combination and arrangement of parts, as will be more fully described and particularly pointed out in the appended claims.

In the accompanying drawings,—Figure 1 30 is a perspective view of the holder attached in position to a vest pocket and supporting a pencil; Fig. 2 is a central longitudinal sectional view of the holder and a section of a pencil; Fig. 3 is a cross sectional view on the line 3—3 of Fig. 2; Fig. 4 is a plan view of a 35 flat piece of spring metal of which the holder is made.

As shown in the drawings, the holder is made from one continuous piece of flat spring 40 metal having a body portion 1 of preferably rectangular form and an elongated shank or tongue 2 extending at right angles from one of the side edges of the body portion, said tongue having two oppositely disposed laterally 45 projecting lugs or extensions 3 near its outer or free end and terminating at said end in two diverging teeth 4.

In the construction of the invention the ends of said body portion 1 are bent inward 50 to form resilient clamping members 5 adapted to clamp the body of the pencil or pen,

and each of the side edges of the body portion is turned or rolled in to provide a bead 55 6 to enable the holder to be easily slipped on or off a pencil or pen and adjusted to the desired position thereon.

The inner end of the elongated shank or tongue is then bent inwardly over the clamping members on a suitable groove, is extended horizontally to a point directly over or adjacent the outer ends of the clamping members 5, and is then bent over back on itself and extended in an opposite direction to provide a garment clamping member 7, the outer or free end of which is bent in approximately at right angles to provide a jaw 8. The lugs or extensions 3 are bent in under the inner end of the garment clamping member to fasten the two parallel oppositely extending members thereof securely together. 70

In the application of the invention, the clamping members 5 are arranged on the body of the pencil or pen at a suitable point, and the teeth of the garment clamping member engage the garment to which the same is attached. The extreme inner end of the tongue 2 serves as a spring pivot or fulcrum for the clamping members and normally maintains it at a plane parallel or substantially parallel with the plane of the clamping 75 members 5.

Having described my invention, what I claim as new and desire to secure by Letters-Patent, is:

A holder of the class specified, made from 85 flat spring metal and comprising pencil and garment clamping members, respectively, the latter being extended for a portion of its length at an angle to the former and then bent back upon itself and extended beyond 90 the inner end of the same, the outer portion of the garment clamping member being formed at opposite side edges and at a point adjacent to the inner end of the inner portion of said member with engaging means for 95 rigidly and detachably connecting said portions, the outer or projecting end of the outer portion of the garment clamping member being adapted to engage a garment, that portion of said last mentioned member extending outwardly beyond the inner end of the pencil clamping member constituting a fin- 100

gerpiece adapted to be depressed to disengage the garment clamping member from the garment, and the extreme inner end of said last mentioned member acting as a spring 5 pivot and exerting pressure upon the finger-piece to normally maintain it in engagement with the garment.

In testimony whereof I have hereunto set my hand in presence of two subscribing witnesses.

EDWARD L. SANDS.
